HAMILTON LINDSAY, OF CLEVELAND, OHIO, ASSIGNOR TO THE LINDSAY WIRE WEAVING COMPANY, OF CLEVELAND, OHIO, A CORPORATION OF OHIO.

WIRE BELT AND PROCESS FOR MAKING SAME.

Application filed December 23, 1921. Serial No. 524,554.

An object of this invention is to provide a woven wire belt adapted for use in a paper making machine and so formed as to increase its durability over the belts now employed.

Woven wire belts, in Fourdrinier machines, carry the pulp before it has been sufficiently solidified to be carried by fabric belts and travel over suction boxes which draw the water down through the interstices of the belt. In order that the suction may be at all efficient, the belt must travel in contact with the top of the suction box and the result is that the warp wires wear grooves in the upper surface of the suction box. These grooves leave sharp ridges between them and these ridges frequently tear and injure the belt. While the lay wires are sometimes torn, the difficulty is particularly pronounced with the lacing which connects the ends of the belt, as such lacing, passing diagonally back and forth and overlying both the warp and lay wires, necessarily encounters these ridges. The above mentioned difficulty is so serious, that in many cases, mechanism has been employed to oscillate the suction boxes so that the warp wires will wear them down evenly at the top instead of grooving them. This system, however, increases the expense and is not altogether satisfactory in accomplishing the desired result.

I propose to obviate the difficulty described by weaving a belt in which the warp wires do not run absolutely parallel with the length of the belt, but, on the contrary, are at a very acute angle thereto, first in one direction and then in the other. The amount of divergence of the warp wires is in reality very slight; being simply a distance corresponding to two or three wires in the weave for a length of many feet. Such divergence, however, prevents the formation of the troublesome grooves because the region worn by any wire shifts slightly back and forth on the top of the suction box so that the whole top is worn down evenly.

In the weaving of my new belt, the slight divergence continues in one direction as stated for a number of running feet and then the divergence is back to the starting point and then in the same direction as at first and so on, so that the salient points at

the edge are all in the same straight line. Thus the belt as a whole is true and travels in the usual manner over the rollers in the Fourdrinier machine and at the same time accomplishes the desired result of evenly wearing the suction boxes.

My invention comprehends not only such a belt as described, but the method of weaving its fabric which includes the longitudinal shifting of the cloth beam first in one direction and later in the reverse direction. This shifting takes place periodically and may be readily accomplished either manually or mechanically. Following each shifting, the woven fabric as it winds onto the cloth beam gradually assumes a true position; after which the cloth beam is shifted in the opposite direction.

This invention is hereinafter more fully explained in connection with the drawings, and the essential characteristics are summarized in the claims.

In the drawings, Fig. 1 is a side elevation and Fig. 2 a front view illustrative of a loom for weaving the fabric of my belt; Fig. 3 is a plan of a strip of such fabric, the divergence at the edges being much exaggerated for clearness of illustration; Fig. 4 is an exaggerated plan of a portion of such fabric; Figs. 5, 6 and 7 are views, also exaggerated, illustrating the direction of the warp wires in different regions of the belt; Fig. 8 is a plan on an enlarged scale of the laced end-portions of the belt; Fig. 9 is an edge view thereof.

In Figs. 1 and 2, 1 indicates the usual warp beam; 2 a cloth guide-roller; 3 the cloth beam, and 4 the batten of the loom. The warp wires A¹, originally mounted in circumferential grooves in the warp beam, receive the shoot wires by means of a shuttle traveling along the batten in the usual manner; thus producing the fabric A which extends over the guide roll 2 and is wound onto the receiving roll or cloth beam 3.

The usual mechanism may be employed for gradually rotating the cloth beam to take up the woven fabric, but such mechanism is omitted in the drawing for clearness of illustration. I have shown, however, in Fig. 2, a mechanism which may be employed for shifting the cloth beam axially. This is shown as comprising a screw 5 threaded in a bracket 6 and having a

swivel connection 7 at its inner end with the cloth beam axle and having at its outer end a hand wheel 8 by which it may be turned. This particular mechanism however, is simply illustrative of any convenient means (operated manually or mechanically) for shifting the cloth beam.

In weaving of my fabric, after it has started on the cloth beam, the beam is shifted 10 axially in one direction or the other, a distance corresponding approximately to two or three times the distance from one warp wire to the next. This causes the warp wires from the batten to the cloth beam to 15 lie slightly askew. The angular divergence however, is very slight, owing to the distance between the cloth beam and the batten.

As the weaving progresses, the fabric is 20 gradually wound onto the cloth beam, it automatically travels in the direction from which the cloth beam has been shifted; that is to say, it tends to true itself and in the course of a number of feet of wound fabric, 25 corresponding for instance to two or three rotations of the cloth beam, it becomes true. Then the cloth beam is shifted by means of the hand wheel or equivalent mechanism a corresponding distance in the opposite direction and is left in that position until the 30 fabric gradually traveling in the other direction as it winds up, trues itself. The true edges which the fabric tends to reach are indicated by two lines X—X in Fig. 2, 35 and it will be seen in this figure that the cloth beam has been shifted toward the right of these lines.

Fig. 3 indicates in a much exaggerated form, such fabric as produced by the loom 40 when manipulated in the described manner. Assuming that this fabric was produced by movement in the direction of the arrow, then the cloth beam was at its extreme left position at the points indicated by the lines 45 L—L and at its right hand position in the regions indicated by the lines R—R.

In Fig. 4, I have shown on a scale larger than Fig. 3, a portion of the fabric and have indicated in Figs. 5, 6 and 7, the direction 50 of the warp wires A³ for various regions of the fabric shown approximately at A⁵, A⁶, and A⁷ respectively on Fig. 4. The lay or shoot wires A⁴ in all regions of the belt are at right angles to the edge lines in 55 which the salient points at the edge of the fabric line; such edge lines being shown at E in Figs. 3 and 4. As these two edge lines are parallel and at right angles to the rollers over which the belt travels in the Fourdrinier machine, the belt runs perfectly true 60 notwithstanding the divergence of the warp wires.

In Figs. 8 and 9 I have indicated, at B, some of the lacing for the meeting ends of 65 the belt. This lacing passes diagonally

across both the lay wires and the warp wires and thus overlies them both. It is preferably a finer wire than the wire of the fabric and after being laced the seam is smoothed down as much as possible, but the fact is 70 inevitable that as the belt travels, the lacing wires will travel across and in close contact with any ridges in the edge of the suction boxes, and are therefore particularly susceptible to being worn by such ridges. 75 With my belt however, the gradual divergence of the warp wires maintains the wire on the suction boxes true so that there are no ridges to engage the lacing.

Thus my invention provides a weave 80 wherein the warp wires extend parallel to each other first in one direction and then in another direction to form in effect a herring bone shape. The angular divergence of the warp wires out of the normal direction however, is very slight so that the belt may carry pulp in a zone substantially equal to the full normal width thereof. To effect this result, the lateral displacement 85 of the warp wires due to the divergence during the weaving process constitutes only the distance between a few warp wires, these being sufficient to overcome the grooving of the suction boxes. Accordingly, pulp may be carried in a zone having a width 90 defined by contiguous straight lines which bound the re-entrant angles on opposite sides of the belt. The displacement of the warp wires is so slight however, that this 95 zone is substantially equal to the full normal width of the belt. 100

While not confining myself to any particular dimensions, I may say, by way of illustration, that I have produced satisfactory results in a belt having a mesh of 40 to the 105 inch longitudinally and 60 to the inch transversely and wires of approximately 30 gauge, by a shift of the cloth beam $\frac{1}{8}$ of an inch for each 8 feet of length of fabric. The fabric so made is used in the identical 110 manner of the ordinary fabric—in fact the difference is hardly discernible with the naked eye—but the desired even wear on the suction boxes is obtained without the necessity of oscillating them (frequently impracticable in the other machines) and the net result is the prolonged life of the belt. 115

I claim:—

1. A woven wire belt comprising a fabric having the warp wires extending at an angle slightly different from a right angle to the weft wires, such oblique angle being slightly obtuse for a considerable distance and then slightly acute. 120

2. A woven wire belt comprising a fabric having the warp wires slightly diverging from the longitudinal center line of the fabric, such diversion in the course of many feet of the fabric being equal to the distance 125 between the warp wires. 130

3. A woven wire belt comprising a fabric having the ends thereof laced together by wires passing diagonally over both warp and weft wires, said warp wires being slightly divergent from the longitudinal center line of the fabric, such divergence in the course of many feet of the fabric being equal

to the distance between a few warp wires, and the weft wires being at right angles to such longitudinal center line. 10

In testimony whereof, I hereunto affix my signature.

HAMILTON LINDSAY.
